UNITED STATES PATENT OFFICE.

ISAAC S. MCGIEHAN, OF NEW YORK, N. Y.

DESIGN FOR A PNEUMATIC TIRE.

SPECIFICATION forming part of Design No. 34,932, dated August 13, 1901.

Application filed April 9, 1901. Serial No. 55,114. Term of patent 7 years.

To all whom it may concern:

Be it known that I, ISAAC S. MCGIEHAN, a citizen of the United States, residing in New York city, county and State of New York, have 5 invented and produced a new and original Design for Pneumatic Tires for Vehicles, of which the following is a specification, reference being had to the accompanying drawings, which form part thereof.

10 Figure 1 is a side elevation of a pneumatic tire, showing my new design; and Fig. 2, a transverse section thereof.

As shown in the drawings, the leading and essential feature of my design consists of a 15 flat outer periphery or tread portion *c*, with a portion of the sides flaring outwardly to the

points *b b*, and a curved inner peripheral portion *e* extending between the points *ff*. Between the points *b f* on each side is a depressed convex panel *d*, running cylindrically 20 around the side of the tire.

Having thus fully described my invention, what I claim is—

The design for a pneumatic tire, as herein shown and described. 25

In testimony that I claim the foregoing invention I have hereunto set my hand this 5th day of April, 1901.

ISAAC S. MCGIEHAN.
